UNITED STATES PATENT OFFICE

141,947

DESIGN FOR A PICTURE FRAME OR SIMILAR ARTICLE

Milan E. Gabriel, New York, N. Y.

Application January 26, 1945, Serial No. 117,610

Term of patent 3½ years

(Cl. D29—20)

To all whom it may concern:

Be it known that I, Milan E. Gabriel, a citizen of the United States, residing at New York, in the county of New York and State of New York, have invented a new, original, and ornamental Design for Picture Frames or Similar Articles, of which the following is a specification, reference being had to the accompanying drawing, forming part thereof.

Fig. 1 is a perspective view of a picture frame, showing my new design, and

Fig. 2 is a front elevational view thereof.

I claim:

The ornamental design for a picture frame or similar article, substantially as shown.

MILAN E. GABRIEL.
